UNITED STATES PATENT OFFICE.

THOMAS O. MUDD, OF LAREDO, TEXAS.

RIFLE-BOLT.

1,305,830.

Specification of Letters Patent. Patented June 3, 1919.

Application filed October 2, 1916. Serial No. 123,435.

To all whom it may concern:

Be it known that I, THOMAS O. MUDD, a citizen of the United States, residing at Laredo, in the county of Webb and State of Texas, have invented new and useful Improvements in Rifle-Bolts, of which the following is a specification.

The object of my invention is to provide a rifle bolt which may be substituted for the bolt now in use in the Springfield rifle, without necessitating any changes in the rifle, and to construct said bolt of a materially less number of parts.

A further object of my invention is to provide a rifle bolt of simple construction, thereby facilitating the assembling and disassembling of the bolt for cleaning, oiling, etc.; a further object of my invention is to provide a rifle bolt which is, for all practical purposes dust proof; a still further object of my invention is to reduce the length of the striker.

A further object of my invention is to so construct the bolt that the parts thereof may be withdrawn for cleaning, etc., without removing the bolt from the receiver.

A still further object of my invention is to eliminate all screws and springs, except the main spring of the bolt, and with these and other objects in view my invention consists of the parts and combination of parts as will be hereinafter pointed out.

A further object of my invention is to construct a rifle bolt that can be taken apart by a simple turn of the cocking piece, when this together with the cocking sleeve, and safety can be removed for cleaning, oiling, etc., without removing the main bolt casing from the receiver.

A further object of my invention is to so construct a rifle bolt, that the main spring, firing pin bar, and striker can be taken apart for cleaning, oiling, etc., by a slight turn of the firing pin bar head.

A further object of my invention is to construct a rifle bolt in which the firing pin bar is extra heavy and strong, and which can be used almost indefinitely, notwithstanding it is the part that performs the hardest work.

A further object of my invention is to construct a rifle bolt that has a striker, that is very easy to remove, and almost inexpensive to replace.

In the drawings:—

Figure 1 is a vertical longitudinal sectional view of a standard U. S. magazine

rifle, (model of 1903) embodying my invention.

Fig. 2 is a side elevation of the receiver and bolt removed from the rifle, the parts being in fired position.

Fig. 3 is a similar view showing the handle about to be depressed to lock the bolt.

Fig. 4 is a detail elevation showing the handle in depressed or lowered position.

Fig. 5 is a side elevation of the firing pin bar and striker, or firing pin, secured thereto.

Fig. 6 is a plan view of the striker detached.

Fig. 7 is a perspective view of the assembled bolt removed from the rifle.

Fig. 8 is a front elevation of the bolt detached from the rifle; Fig. 9 is a transverse section through the cocking sleeve 26 and associated parts; Fig. 10 is a rear elevation of the cocking sleeve 26.

Fig. 11 is a side elevation of the safety catch.

Fig. 12 is a side elevation of the bolt head.

Fig. 13 is a side elevation of the extractor.

Fig. 14 is a detail plan view of the rear end of the bolt.

The rifle used for the purposes of illustrating my invention is the 1903 model of the U. S. magazine rifle and therefore it will be unnecessary to describe the same in detail.

According to my invention the bolt 1 is provided at its forward end with top and bottom locking lugs 2 and 3 and the usual operating handle 4. The top lug 2 is provided with a slot 2^a through which the usual ejector passes as the bolt is moved backward and forward. The rear end 5 of the bolt is of reduced diameter and is provided with a shoulder 6 and recesses 7, said recesses being adapted to receive the safety latch to be hereinafter described.

The bolt head 9 is provided with an opening 10 through which the striker projects, the outer end of the head having an opening 10 terminating at the top in two upwardly extending spaced lugs 11, said collar having a transverse groove 12 at the bottom. The bolt head is provided with two rearwardly extending arms 13, 14, the arm 13 being grooved at 13^a longitudinally in alinement with the space between the lugs 11 to receive the extractor 15, the forward end of the extractor being flush with the front walls of the lugs 11. Lugs 16 are formed on the arms 13, 14 which are adapted to enter longitudinally extending grooves 17 in the bolt which

grooves intercept an annular groove 17^a in the inner face of the bolt, whereby when the firing head is revolved it is locked to the bolt. The firing pin bar 18 is provided at its forward end with a collar 19 beyond which projects a flat member 20 which is adapted to fit singly between the arms 13, 14 of the bolt head, the forward end portion of the member or head 20 being provided with an undercut groove 21 into which the striker or firing pin 22 is adapted to be secured. The striker is provided with a reduced central portion 23 and a head 24, said head engaging the undercut portion of the groove 21 whereby the striker is firmly, but readily detachably, secured to the firing pin bar 18. It will be noted that by my invention I am enabled to materially reduce the length of the striker. The rear end of the striker bar 20 is flattened on two of its sides and is provided with two pairs of oppositely disposed lugs 25. The cocking sleeve 26 is adapted to have a neat sliding fit on the reduced portion 5 of the bolt and is revolvably mounted thereon, the firing pin bar 18 extending rearwardly beyond the cocking sleeve; said firing pin bar being secured to the cocking sleeve by means of the cocking piece 26^b which is provided with a forwardly extending arm 28 having a lug 29 which lug enters a groove 30 in the cocking sleeve. The cocking sleeve has a forwardly extending cam lip 26^a which co-operates with the handle 4 to move the sleeve rearwardly. The cocking piece 26^b has an elongated opening 31 in which are lugs 32 adapted to interlock with the lugs 25 on the firing pin bar whereby these two parts are secured together. The cocking sleeve 26 is provided with longitudinally extending grooves 33, 34 and a lug 35 positioned between said grooves said lug co-operating with the sear nose. A safety 36 is mounted on the cocking sleeve and is provided with an arm 37 having cams which are adapted to engage the recesses 7 on the bolt to lock the bolt. The main spring 39 is mounted in the bolt and disposed around the firing pin bar 18. The bolt 1 moves backward and forward and revolves in the rifle receiver A, carrying a cartridge from the magazine or one placed by hand in front of it, and places same in the rifle barrel or chamber when shoved forward, and supports the head when fired. At the time that the cartridge is placed in the rifle chamber the hook of the extractor 15 catches in the cartridge groove, and holds the shell until it is ejected. The cocking piece 26^b unites the parts of the bolt mechanism by a simple tongue and groove arrangement. The cocking piece 26^b also engages and holds the firing pin bar 18 by a tongue and groove arrangement. The arrangement permits of the bolt being easily

taken apart by a slight turn of the cocking piece for cleaning, oiling, etc., without removing the main bolt casing 1 from the rifle receiver on the rifle. The safety 36 when turned to the left permits the operation of 70 the bolt and other parts for loading and firing, ejecting the shell, etc., or when turned to the right locks the bolt by engaging the lugs as shown on horizontal arm 37 in grooves 7. The safety when turned to the 75 right also prevents the rifle from being fired when the bolt is cocked. The lugs 2 and 3 serve to lock and hold the bolt in grooves in the bolt receiver when being fired, and may be termed locking lugs. 80

The lugs 16 of bolt bar head 9, hold the main spring 39 in place within the bolt by interlocking with grooves 17 in bolt casing, when cocking piece 26^b, cocking sleeve 26 and safety 36 are removed from the bolt for 85 cleaning, oiling, etc. Main spring 39 and firing pin bar 18 together with striker pin can be removed from main bolt casing for cleaning, oiling, etc., by a slight turn of bolt bar head 9 which disengages lugs 16 on 90 same from inner grooves 17 in main bolt casing.

To open the bolt, raise the handle 4 until it comes in contact with the left side of the receiver A and pull directly to the rear. Raising the handle rotates the bolt and separates the locking lugs from their locking shoulders in the receiver, with which they have been brought in close contact by the power pressure. This rotation causes the cocking 95 cam of the bolt to force the firing pin to the rear, drawing the point of the striker into the bolt, rotation of the firing pin being prevented by the lug on the cocking piece projecting, through the sleeve, into its groove in 100 the receiver. As the sleeve remains longitudinally stationary with reference to the bolt, this rearward motion of the firing pin, and consequently of the striker, will start compression of the main spring 39, since the 105 rear end of the latter bears against the front end of the barrel of the sleeve and its front end against the collar 19 of the firing pin. 110

During the rotation of the bolt a rear motion has been imparted to it by the usual extracting cam, coming in contact with the usual extracting cam of the receiver, so that the cartridge case will be started from the chamber. 115

The bolt is then drawn directly to the rear, the parts being retained in position by the cocking piece nose remaining in the cocking notch and locked by the sleeve lock engaging its notch in the bolt. 120

The position then occupied by the parts 125 is shown in Fig. 4, and the piece is ready to fire.

To pull the trigger, the finger piece must be drawn to the rear until the contact with the receiver is transferred from its bar to 130

the heel, which gives a creep to the trigger, and then until the sear nose is withdrawn from in front of the cocking piece.

Just before the bolt is drawn fully to the rear, the top locking lug strikes the heel of the usual ejector, throwing its point suddenly to the right in the lug slot. As the bolt moves fully to the rear, the rear face of the cartridge case strikes against the usual ejector point and the case is ejected slightly upward and to the right, from the receiver.

It will be noted that in the system of the bolt mechanism the compression of the main spring, the setting of the cartridge in, and the starting of the empty case from the chamber are entirely done by the action of the cams.

The piece may be cocked either by raising the bolt handle until it strikes the left side of the receiver and then immediately turning it down or by pulling the cocking piece directly to the rear.

After the bolt has been pulled to the rear and the cartridge advanced to loading position the bolt is pushed forwardly to the position shown in Fig. 3. Continued pressure in a forward direction on the handle advances the handle and bolt until the handle comes in contact with the receiver as shown in Fig. 4.

What I claim is:

1. In a rifle bolt, the combination with a firing pin bar, and a striker secured to the forward end thereof, of a cocking sleeve movably mounted on the bolt, and a cocking piece, secured to said firing pin bar and cocking sleeve.

2. In a rifle bolt, the combination with a

firing pin bar, and a striker secured thereto, of a cocking sleeve movably mounted on the bolt, and a cocking piece detachably locking the cocking sleeve and firing pin bar together.

3. In a rifle bolt, the combination with a firing pin bar, and a striker, of a cocking piece detachably secured to said firing pin bar, whereby the cocking piece, cocking sleeve and safety can be removed from the bolt without removing the bolt from the receiver, and wherebv main spring, firing pin bar, and firing pin can be removed from the bolt by a slight turn of the firing pin head.

4. In a rifle bolt, the combination with a bolt head, arms extending rearwardly therefrom, locking lugs on said head, of a firing pin, a flat member extending forwardly therefrom and constructed to fit between said arms, and a comparatively short striker secured to said member.

5. In a rifle bolt, the combination with locking lugs on the forward end of the bolt, a bolt head secured in the forward end of the bolt, arms extending rearwardly from said head, an extractor mounted on and carried by said head, a firing pin bar, a flat member extending forwardly from said bar and seated between said arms, a striker secured to said member, a cocking sleeve movably mounted on the rear end of the bolt, a cocking piece interlocking with the firing pin bar and cocking sleeve, whereby the cocking sleeve is locked with the said bar.
